CLAIM

The ornamental design for an illuminated control device, as shown and described.

DESCRIPTION

FIG. 1 is a front view showing a first state in a sequence of an illuminated control device showing our design;

FIG. 2 is a left side view thereof;

FIG. 3 is a right side view thereof;

FIG. 4 is a top view thereof;

FIG. 5 is a bottom view thereof;

FIG. 6 is a front view showing a second state in a sequence thereof;

FIG. 7 is a front view showing a third state in a sequence thereof;

FIG. 8 is a front view showing a fourth state in a sequence thereof;

FIG. 9 is a front view showing a fifth state in a sequence thereof;

FIG. 10 is a front view showing a sixth state in a sequence thereof;

FIG. 11 is a front view showing a seventh state in a sequence thereof; and,

FIG. 12 is a front view showing an eighth state in a sequence thereof.

The gray shaded elements depict illumination.

The dashed broken lines illustrate portions of the control device which form no part of the claimed design.

The dot-dot-dash broken lines illustrate boundaries which form no part of the claimed design.

The appearance of the claimed design transitions from the first state to the last state in the sequence. The process or period in which one state transitions to another state forms no part of the claimed design.

1 Claim, 10 Drawing Sheets
